DESIGN FOR A CHILD'S BANK

Katherine Heinrich Stovner, Denver, Colo.

Application March 24, 1947, Serial No. 137,843

Term of patent 7 years

(Cl. D34—11)

To all whom it may concern:

Be it known that I, Katherine H. Stovner, a citizen of the United States, residing at Denver, in the county of Denver and State of Colorado, have invented a new, original, and ornamental Design for Child's Bank, of which the following is a specification, reference being had to the accompanying drawing, forming part thereof and in which:

Fig. 1 is a front perspective view of a child's bank showing my new design;

Fig. 2 is a rear elevation of the same; and

Fig. 3 is an end elevation of the same.

I claim:

The ornamental design for a child's bank, as shown.

KATHERINE HEINRICH STOVNER.
